UNITED STATES PATENT OFFICE.

JOSEPH PAGLIARUL, OF CHICAGO, ILLINOIS, ASSIGNOR TO JOSEPH E. SMYTH, OF CHICAGO, ILLINOIS.

WIRE-STITCHING MACHINE.

1,215,312.

Specification of Letters Patent.

Patented Feb. 6, 1917.

Application filed June 22, 1914. Serial No. 846,432.

To all whom it may concern:

Be it known that I, JOSEPH PAGLIARUL, a citizen of the United States, residing in the city of Chicago, county of Cook, and State of Illinois, have invented certain new and useful Improvements in Wire-Stitching Machines, of which the following is a specification.

My invention relates to improvements in wire stitching machines and refers more particularly to wire stitching machines employed for stitching together sheets of paper forming books of varying thicknesses.

Among the salient objects of the invention are, to provide an improved wire stitching machine in which the legs of the staple are at all times of equal length, whatever may be the length of the staple being used; to provide a construction of the class described in which the cutting-off mechanism may be adjusted to cut off varying lengths of wire to form the staple, while with the same motion the wire-feed is adjusted to feed forward a wire having an increase or decrease in length equal to twice the amount of movement of the adjustable cutting device; to provide an improved adjustment for the wire-feeding mechanism which will permit of an extremely fine adjustment of the forward feed of the wire, while at the same time the ratio between the adjustment of the cutting mechanism and the wire-feeding mechanism is unchanged; to provide an improved cutting-off mechanism which will permit of the ready removal and replacement of parts subject to wear or disarrangement; to provide an improved construction to positively hold the wire while the staple length is being cut off; to provide improved mechanism for paying off the raw wire from the feed spool while said feed spool is subjected to a positive braking effect independent of the amount of wire on said spool; to provide an improvement in the forming mechanism which will prevent the improper accidental cutting off of the end of the wire blank due to lack of straightness of the wire; and, in general to provide an improved wire stitching machine of the character referred to.

My invention consists of the matters hereinafter described and more particularly pointed out in connection with the accompanying drawings, in which—

Figure 1 is a front elevation of the ma-

chine as a whole showing the principal operating parts;

Fig. 2 is a side elevation of the machine showing certain parts broken away or omitted to clarify the drawing; 60

Fig. 3 is an enlarged fragmentary view of a portion of Fig. 1 showing the cutting-off mechanism;

Fig. 4 is a reverse view of a portion of Fig. 1 showing the staple length adjusting mechanism; 65

Fig. 5 is a fragmentary section taken along the line 5—5 of Fig. 3;

Fig. 6 is a view in elevation of a portion of the cutting off unit removed from the machine; 70

Fig. 7 is a side view of Fig. 6;

Fig. 8 is a section taken along the line 8—8 of Fig. 6;

Fig. 9 is a section taken in plan along the line 9—9 of Fig. 4;

Fig. 10 is a sectional view taken along the line 10—10 of Fig. 1; and

Fig. 11 is an under side view of Fig. 10 partly in section taken along the line 11—11. 80

Referring to the drawings, 1 represents the frame of the machine to the front of which is secured the flat upstanding casting 2 upon which are mounted the various mechanisms to be described. 3 is the stitching saddle of the machine below which is arranged the leg-bending or crimping mechanism, which is not shown but may be of any particular type desired, as it forms no part of my present invention. The machine 90 as a whole is driven by means of a pulley 4 to which is keyed the shaft 5 journaled in the frame 1 and the casting 2 and projecting through the latter.

To the upper part of the casting 2 is secured an upstanding bracket arm 6 which carries the spool 7 with its associated braking mechanism, the spool itself being journaled upon a horizontal pin 8 fixed in the upper end of said bracket 6. The spool is 100 maintained in position on the pin 8 by means of a star-shaped spring washer 9 which is prevented from coming off the end of the pin 8 by means of a cotter pin 10. This washer, however, is not intended to provide any great amount of braking effect, which is taken care of by the brake-lever 11 which carries a leather pad 12 long enough to bear against each flange of the spool. The brake-lever 11 is pivoted upon a horizontal pin 13 110

fixed in the oblique arm 14 of the bracket 6, and the lower end of this lever is operated upon by one end of the spring-actuated pivoted arm 15. The latter is pivoted upon a pin 16 also fixed in the bracket 6 and is urged in a direction so as to twist the arm to apply the brake by means of a coil spring 17 one end of which is secured to the pin 16 and the other end engages the horizontal portion of the arm. This arm is formed from suitable sheet metal and the end remote from the bracket is bent down and shaped so as to form a circular track for the wire and V-shaped in cross-section. The wire is prevented from jumping out of the track by means of several wire eyes 17^a secured in the center of the arm. The radius of the circular portion of the arm is such as to deliver the wire substantially in a straight tangential line to the wire-straightening mechanism designated as a whole 18. It will be noted that the amount of tension or frictional drag imparted to the wire by the spool take-off mechanism just described, is determined by the tension of the spring 17, and is independent of any friction due to the rotation of the spool on its spindle. When the wire is pulled into the machine by the feeding mechanism, the end 19 of the lever 15 swings down, due to the pull of the wire, and releases the brake 12 slightly permitting the spool to rotate.

The feeding forward of the wire is accomplished by the cam-operated feed lever 42. This lever 42 is mounted upon a horizontal pivot pin 43 fixed in the front of the main frame casting 2 and is normally forced in a clock-wise direction by means of a comparatively stiff coil spring 44 which is wound around said pivot. The backward movement of the lever is limited by the adjustable stop-pin 45 which engages a circular notch in the back edge of the lower arm of the lever. The upper end of the lever is pivoted with a pin 46 upon which is rotatably mounted a cam-roller 47, the latter being adapted to be engaged by the cam surface 48 upon the cam member 49 which is securely keyed to the operating shaft 5. It will be self evident from an inspection of Fig. 1 that as the cam member 49 rotates, the cam surface 48 will engage the roller 47 and cause the lever 42 to make a partial rotation in an anti-clock-wise direction, its angular motion ceasing after the roller passes beyond the point 50, and it will not begin to recede until it is disengaged by the cam surface following behind the point 51. It will be noticed that this cam surface is so shaped that it does not determine the rear position of the lever 42, this being taken care of by the stop-pin 45. Thus the amount of swing of the lever 42 can be adjusted by changing the position of the stop-pin 45, since the limit of forward motion is always

the same, being fixed by the relation of the cam surface 48 to the cam-roller 47 and the pivot 43. Upon the lower end of the lever 42 is mounted an arc-shaped track member 52 which is grooved throughout the greater portion of its length to prevent the wire from becoming accidentally displaced. The front end of this arc-shaped track is cut away down to the bottom of the groove and for a short distance back from the front end of the track to form a seat for the gripping roller 53. The latter consists of a circular section of tool steel having serrations or teeth cut into its periphery which is rotatably mounted upon a pin 54 fixed into the end of the swinging arm 55, which is itself pivoted upon a pin 56 fixed in the arm 42. The arm 55 is of a sufficient thickness to be bored out to accommodate a coil spring 57 which surrounds the reduced stem portion of a plunger 58, the latter being thus forced out by the spring against the small angle plate 59 which is secured to the edge of the feed lever 42 by the screw 60. It will be noticed that the pivot 56 is located some distance to the right of an imaginary line connecting the pin 54 with the pivot 43, and the spring 57 thus tends to force the gripping roller 53 into engagement with the cut away portion of the arc-shaped track forming the gripping seat. It is thus clear that when the feed lever moves forward in an anti-clock-wise direction, the roller 53 will grip the wire tightly and push it forward into the cutting and forming mechanism. When the lever moves backward, however, in a clock-wise direction there is no tendency for the lever to grip the wire, because the spring 57 is relatively weak and allows the arm 55 to swing slightly on its pivot and thus release the wire as the lever moves backward. It is understood that the arc-shaped track 52 forms part of a circle having for its center the pivot 43, the distance from said center being such that the direction of the wire as it leaves the wire-straightening mechanism is a tangent to the bottom of the groove in the track. Thus there is no tendency to bend the wire as it is being fed forward by the feed-lever which is also so placed as to deliver the wire in a substantially straight line to the cutting mechanism.

Referring to Figs. 4 and 9, it will be seen that the stop-pin 45 is secured in an arm of the member 61 which is a flat sector-shaped piece of steel pivoted at the rear of the main frame casting 2 and co-axially upon the back end of the fixed pivot 43. Substantially vertically below the pivot 43 I have secured in the member 61 a stud 62 which projects rearwardly so as to be engaged by a vertical slot 63 in the upper portion of the small plate 64 secured to the top of the sliding plate 65. The latter is slidably positioned

and held into engagement with the back of the main frame casting 2 by means of a flat-headed stud 66 which projects through a slot 67. The cutting-off mechanism as a whole 5 is mounted upon a rectangular block 68 which is provided with a rectangular portion 69 extending through a horizontal slot 70 formed in the main frame casting 2 and is secured to the plate 65 by a long screw 71 10 which passes freely through the block 68 and is threaded into the plate 65. The respective surfaces of the block 68 and the front and rear of the main frame casting 2 are finished so as to form suitable sliding 15 surfaces. To the rear of the plate 65 is secured a rectangular plate 72 which is drilled out at its end to form a bearing for the end of the adjusting screw 73, the latter being provided with a groove 74 which is engaged 20 by a pin 75 secured in the block 72. The adjusting screw 73 is threaded so as to coöperate with the longitudinal threaded bore of the rotatable adjusting member 76, the latter having a reduced neck portion rotatably 25 seated within a mounting 77 and having a pair of integral collars 78 which prevent longitudinal movement of the adjusting member 76 when the latter is turned. The member 76 is furnished with a suitable 30 knurled head 79 of a sufficient diameter to enable it to be easily adjusted.

On referring to Fig. 4 it will readily be understood that on turning the head 79, the plate 65 will move correspondingly in a 35 horizontal direction and will carry with it away from the center of the forming machine both the cutting mechanism carried by the block 68, and also, by virtue of the slot 63, it will move the stud 62 an equal 40 amount. The stud 62 is secured in the member 61 at a distance from the center of the pivot 43 precisely equal to one-half of the distance between said pivot 43 and the bottom of the groove in the arc-shaped track 52 45 on the end of the feed lever. It is thus apparent that a horizontal movement of the cutting mechanism away from the center of the machine results in a backward movement of the arc-shaped track. The amount of 50 such backward movement measured on the circumference of the track is equal to twice the amount of horizontal movement of the cutting mechanism. Such horizontal adjustment of the cutting mechanism will thus 55 result in an increase or decrease in the length of the wire fed by each oscillation of the lever, the change in length being equal to twice the amount of movement of the cutting mechanism horizontally away from or toward the center of the machine. The amount 60 of adjustment required is usually not very large, and the position of the stud 62 consequently does not seriously depart from its 65 average position vertically below the pivot 43 and thus the ratio of two to one between

the increase of the length of the wire fed and the movement of the cutting mechanism toward or away from the center of the forming mechanism is not seriously disturbed throughout the range of adjustment of the wire fed. It should of course be understood that the object of maintaining this proportion is to insure keeping both legs of the staple of precisely the same length, independent of any change in the length of the blank necessary to form staples of different lengths for work of different thicknesses. 70

Referring to Figs. 6, 7 and 8, it will be seen that the block 68, which carries the cutting-off and crimping mechanism, is formed 80 with a removable portion 80 which is located in position by a dowel pin 81, this removable portion 80 carrying the cutting-off plunger while the clamping plunger is mounted in the main body of the block 68. 85 The wire is guided into the cutting-off die by a tubular bell-mouthed cylindrical plug 82 the end of which is threaded and screwed into the block 68. The clamping plunger 83 whose function it is to prevent the wire from 90 being improperly pulled back when the feed-lever is making its backward movement, is located in a vertical bore just behind the guide-block 82. The wire is gripped between the serrated lower end 84 of the clamping plunger and the top of the opposed anvil member 85 which is fixed in a hole bored out beneath the clamping plunger 83. The upper end of the clamping plunger 83 is reduced in cross-section to form a stem 86 95 around which and in the bore 87 is located a coil compression spring 88. The upper end of the latter presses against the sleeve 89 which slides upon the upper end of the stem 86 and is prevented from flying off by 100 means of a transverse pin 90 which is securely fixed in the end of the stem 86, and its ends are long enough to ride freely in the diametrically opposed slots 91 in the sleeve. The upper end of the sleeve is furnished with a comparatively large integral head 92 and the sleeve itself is forced vertically upward by a coil compression spring 93 seated in the enlarged bore 94 extending 105 down into the block 68 a short distance. The clamping plunger is operated and forced into engagement with the wire by the horizontal arm 95 which projects from the side of the cutting-off plunger 96. The serrations of the lower end of the clamping plunger 83 are cut in such a direction as to cross the wire at right-angles to its length, and in order to maintain the plunger in the proper position to keep these serrations facing in the proper direction, the head 92 is 110 formed with a V-shaped notch 97 extending across its diameter and engaged by the arm 95. 115

The cutting-off mechanism proper, comprises the tubular die 98, which is thread- 120

125

130

ed into the removable portion 80 and the circular disk cutter 99 which is mounted upon the outside of the cutting plunger 96. The plunger 96 is provided with a pair of longitudinal tongues 96^a which slide within vertical grooves formed in the block 80. The reciprocatory movement to do the actual cutting off of the wire is imparted to the cutting-off plunger 96 by a reciprocating 5 slide member 100 which has a flat horizontal angular projection 101 which is engaged by a horizontal notch 102 in the back of the cutting-off plunger. The member 100 is normally forced upward by a coil spring 100^a located in a cylindrical bore drilled vertically from its under side, the spring co-operating with a small pin 101^a which engages a small angle piece 102^a secured to the side of the fixed member 103^a by screws 104^a. 10 The vertical shank of the reciprocatory slide 100 is rectangular in cross-section and slides in a vertical rectangular guideway formed in the back of the piece 103 which is fixed to the main casting 2. The upper end of 15 the shank of the plunger 100 carries securely fixed therein a pivot-pin 104 upon which is rotatably mounted a cam roller 105, the latter being engaged by the cam surface 106 formed on the circumference of the main 20 cam member 49. The actual cutting off of the wire takes place when the raised portion 107 of the said cam surface strikes the roller 105 as the cam member rotates (see Fig. 1), and it will be noticed from an inspection of Fig. 8 that in normal position the cutter 99 is positioned a considerably greater distance above the wire than is the serrated end of the plunger 83, this resulting in the wire being securely clamped by 25 the plunger 83 before the cutting-off knife 99 severs the wire blank. The raised portion 107 of the cam surface 106 forms substantially one-half of its circumference and is so positioned on the exterior of the cam 30 that the wire is securely clamped by the plunger 83 while the feed-lever is making its backward movement so as to prevent the wire from being pulled back by the latter as it recedes, whereas, when the feed-lever is 35 feeding forward the wire into the cutting-off mechanism, the plunger 83 is raised out of contact with the wire, which thus moves forward freely.

The forming anvil, shown best in Fig. 10, 40 is located directly in the center line of the machine below the center of the shaft 5, and comprises a cylindrical plunger 108 which slides horizontally in a cylindrical aperture in the front of the casting 2 and co-axial 45 with the bore of the stationary sleeve 109 which is secured in the back of the casting 2 by a set screw 110. The rear end of the plunger 108 is provided with a vertical longitudinal slot 111 which forms a guide 50 around the vertical pin 112 screwed into

the lower side of the sleeve 109. The rear end of the sleeve 109 is partially closed and forms a shoulder for the coil compression spring 113 which operates against the end of the plunger 108 and forces it outwardly 55 into the proper forming position, its movement being limited by the end of the slot 111 striking the pin 112. The outer front end of the plunger 108 is formed with a head 114 which is so shaped as to provide a pair of parallel vertical side surfaces around which the wire is formed and an upper beveled surface 115 and a lower rounded surface 116. A slot 117 is sawn horizontally in the point of the head 114 and the upper 60 edge of this slot at the side adjacent to the cutting mechanism is beveled, as shown at 118, in order to guide the wire into the slot as it is fed forward. The forming plunger 119 is arranged to slide vertically in a rectangular groove formed in the block 120 which is secured to the front of the main frame casting 2 and is reciprocated vertically up and down by a cam roller 121 which is rotatably mounted upon a pin 122 fixed in the upper end of plunger 119, and is engaged by a cam track 123 formed in the front of the cam member 49. The front face of the forming plunger 119 is also slotted out to form a vertical slide-way for the driving plunger 124 which is furnished at its sides with tongues engaging grooves in said slide-way. The lower end of the forming plunger 119 is cut away even with the rear face of the driving plunger 124, and the 65 lower end of the forming plunger thus forms a fork, the arms of which are the proper distance apart to admit the head 114 of the forming anvil as the forming plunger is depressed. The under sides of the forks of the forming plunger are grooved slightly in line with the wire so as to engage the latter and hold it in proper alinement as it is being formed, and the opposed inner faces of the forks are grooved out, as indicated at 125 in Fig. 3, so as to form retaining grooves for the legs of the staple after the forming plunger has operated to form the wire into U-shape. The swinging anvil 126 is made out of a piece of flat steel substantially the same horizontal width as the head 114 of the anvil plunger, and is mounted upon a horizontal pivot 127 secured in the lower end of the slide 128 which reciprocates vertically in a rectangular groove 70 formed in the back of the block 129 which is secured to the face of the block 120. The outer face of the plunger 128 at its upper end carries a stud 130 from the lower side of which depends a pin 131, and around the latter and extending down into the vertical drilled hole 132 of the upper end of the block 129 is a coil compression spring 133 which thus forces the plunger 128 upward 75 and with it the swinging anvil member 126. 80

The latter is also forced inwardly with considerable pressure toward the head 114 by means of the flat clock spring 134 which is secured in a slot in the bolt 135 adjustably secured in the sheet metal guard 136, the latter being mounted upon the block 129 by screws 137. In order to keep the wire in its proper position at the inner end of the slot 117 so that it will be properly engaged by the grooves on the under side of the lower ends of the forming forks, I have provided a guide-finger 138. This guide-finger 138 is mounted to swing upon a horizontal pivot 139 which is fixed in the swinging anvil member 126 and slightly below its pivot 127. The member 126 is provided with a vertical slot in its upper portion to admit the guide-finger and within which the guide-finger swings. The rear edge of this guide-finger 138 is formed V-shaped at its lower end so that the end of the wire in striking it will be deflected and forced into its proper position in the rear of the slot 117, and the front end of the head 114 is notched out in V-shape, as shown in Fig. 11, so as to accommodate the V-shaped lower end of the guide-finger 138. The guide-finger 138 is forced back into its operative position by a light clock spring 140, the lower end of which presses against the wide main spring 134. It will be noticed that the driving plunger 124 is reciprocated vertically by means of a pitman 141 connecting the upper end of the plunger with the crank pin 142 secured in the main cam member 49.

Describing the operation of the forming and driving mechanism, it will be noticed that the end of the wire is fed forward the required amount into the slot 117 and is there accurately positioned by the guide member 138 in readiness to be formed. The forming plunger in its downward movement then engages the wire on each side of the head 114 and directly afterward the cutting plunger severs the blank. The forming plunger then continues its downward movement and forms the ends of the blank into the legs of the staple which embrace the sides of the head 114 and the swinging anvil member 126 and are positively guided by their position in the opposed side grooves in the forks of the forming plunger which continues its downward movement until it engages or substantially engages the upper surface of the book which is being stapled. The forming plunger then remains in this position until the staple has been punched through the paper. The driving is accomplished by the driving plunger 124, the lower end of which is beveled, and in its downward movement forces aside the guide-finger 138 and also engages the bevel surface 115 on the head of the plunger 108 which is thus forced inwardly against the action of its spring. As the downward

movement of the driving plunger continues, the plunger 108 is finally pushed in so as to expose the top of the staple at the end of the slot, and the staple is then engaged by the groove 143 at the point of the driving plunger 124. The staple then of course commences to move downwardly and enters the paper, the swinging anvil member 126 being gradually pushed aside as the bevel end of the driving plunger strikes its upper cam surface until finally it is pushed completely aside by the descending driving plunger which passes beyond the point 144 of the swinging anvil member. The legs of the staple are clamped beneath the book by means of well known mechanism located below the saddle 3, which need not be described.

I claim—

1. In a wire stitching machine, the combination of a frame having an operating shaft, a cam keyed to said shaft, a spring-retracted wire feed lever pivoted to said frame and carrying a roller adapted to be engaged by said cam and having an arc-shaped feed-wire track with gripping means coöperating with said track, a swinging arm having its pivot substantially co-axial with said lever-pivot and provided with a projection substantially halfway between said arc-shaped feed-track and said pivot and with a back-stop adapted to engage said lever, forming mechanism, cutting mechanism at one side of said forming mechanism, and a slide carrying said cutting mechanism and adjustable to vary the distance between said cutting mechanism and said forming mechanism and having a slot the sides of which tangentially engage said projection.

2. In a wire-stitching machine, wire-cutting and clamping mechanism comprising a body portion, a die fixed in said body portion, a knife adapted to slide in said body portion and coöperate with said die, a clamping plunger provided with transverse teeth crossing the axis of the wire, said plunger being adapted to slide in said body portion, parallel with said knife, resilient means for raising said plunger out of contact with the wire, means for depressing said plunger and adapted to prevent rotation thereof and a spring interposed between said plunger depressing means and said plunger.

3. In a wire-stitching machine, wire-cutting and clamping mechanism comprising a body portion, a die secured in said body portion, a knife coöperating with said die and adapted to slide in said body portion, a clamping plunger parallel with said knife and provided at its upper end with a transverse notch, and a pin carried by the end of said knife and arranged to engage said notch and depress the plunger.

4. In wire-stitching mechanism, the com-

bination of a spring-pressed horizontally 5
slidable forming-die having a horizontal slot at its outer end for receiving and forming the wire, the outer end of said plunger
having a vertically extending notch deep enough to expose the wire when located against the rear wall of the slot, and a vertically swinging spring-pressed guide member adapted to enter said notch by movement in a horizontal direction and guide the wire into the bottom of said slot.

5. In wire-stitching mechanism, the combination of a spring-pressed horizontally 15
slidable forming-die having a horizontal slot at its outer end for receiving and forming the wire, the outer end of said plunger having a vertically extending notch deep enough to expose the wire when located against the rear wall of the slot, and a vertically swinging spring-pressed guide member 20
adapted to enter said notch and guide the wire into the bottom of said slot, said guide member being beveled on the side adjacent the wire-feed.

25 6. In a wire-stitching machine, wire-cutting and clamping mechanism, comprising a body portion, a die fixed in said body portion, a knife member adapted to slide in said body portion and coöperate with said die, a clamping plunger slidable in said body portion, parallel with said knife member, a member actuated by said knife member for depressing said plunger, a spring interposed between said body portion and said depressing member for raising the latter, a spring interposed between said depressing member and said plunger, a stem on said plunger slidable in said depressing member, and means for limiting the sliding movement of said stem in said depressing member.

ber, a member actuated by said knife member for depressing said plunger, a spring interposed between said body portion and said depressing member for raising the latter, a spring interposed between said depressing member and said plunger, and a connection between said depressing member and said plunger, permitting a limited sliding movement of the two last named parts relative to each other.

7. In a wire-stitching machine, wire-cutting and clamping mechanism, comprising a body portion, a die fixed in said body portion, a knife member adapted to slide in said body portion and coöperate with said die, a clamping plunger slidable in said body portion, parallel with said knife member, a member actuated by said knife member for depressing said plunger, a spring interposed between said body portion and said depressing member for raising the latter, a spring interposed between said depressing member and said plunger, a stem on said plunger slidable in said depressing member, and means for limiting the sliding movement of said stem in said depressing member.
